BY ATTORNEY

UNITED STATES PATENT OFFICE.

ROBERT EDWARD TWIGG, OF EDGBASTON, BIRMINGHAM, ENGLAND.

GARMENT PRESS.

Application filed December 24, 1925, Serial No. 77,585, and in Great Britain January 8, 1925.

This invention relates to an improved garment press suitable for smoothing and pressing various articles of clothing but more particularly intended for pressing small articles such as neckties. The object of the present invention is to provide a neat effective simple device for smoothing and pressing such garments.

In such garment presses it has been proposed to provide substantially parallel pressure boards which were held apart by spring pressure and for the purpose of applying the pressure to the garment the pressure boards were moved towards one another by means of a screw device or the like. According to the present invention I employ pressure boards which are coupled together by spring means, instead of being pried apart, and the garment to be pressed is folded over a holder or insertion piece which is pushed longitudinally between the pressure boards, so that the act of inserting the garment smooths it out and the spring pressure boards retain it in proper shape with a suitable pressure.

To facilitate insertion of the garment such as a necktie, means are provided for distorting the springs so that they temporarily pry the pressure boards apart. The springs are to this end preferably located laterally of the pressure boards at two or more points at each side and are connected to a side bar so that on moving the side bar inwardly the springs are distorted to pry the pressure boards apart. The pressure boards are also preferably tapered at their ends where the garment is inserted so as to facilitate such insertion. The internal surfaces of the pressure boards which face one another are smooth to effect the desired smoothing action on the garment whilst the external surfaces may be ribbed or corrugated so as to enable the garment press to be placed on a dressing table without danger of scratching the surface of the dressing table.

Although reference is made herein to two pressure boards, it will be understood that the arrangement may be duplicated and the form chosen to be described and illustrated herein is intended only as an example of a suitable method of carrying the invention into effect.

In the drawings:

Figure 1 is a plan view of the improved garment press with a necktie inserted in place.

Figure 2 shows a suitable form of garment holder or insertion piece.

Figure 3 is an end view of the press.

Figure 4 is an end elevation of the insertion piece shown in Fig. 2.

Figure 5 is an enlarged section of the press with a necktie therein.

In carrying the invention into effect as shown, the garment press comprises pressure boards *a* and *b* which are held in substantially parallel relation but a short distance apart by spring means which also serve to couple the boards together. In the form shown, the spring means comprise four C-springs fixed two at each side and laterally of the pressure boards *a* and *b* so that they curve outwardly from a central plane of the pressure boards. The springs *c* are anchored by screws *n* to the pressure boards *a* and *b* as well as to side bars *d* and *e* which are nested in the curved part of the springs *c*. The side bars *d* and *e* act not only as means to couple the springs *c* and enable their distortion for the purposes hereafter explained, but also serve as curved side walls to the press.

It will be understood that the springs *c* hold the pressure boards at their closest normal position when no garment is in the press. By holding the press in the hand and squeezing the side bars *d* and *e*, the springs *c* are distorted and carry the pressure boards *a* and *b* apart. To further assist in this action, I may form the adjacent faces of the side bars *d* and *e* and the pressure boards *a* and *b* bevelled as at *d'* and *a'* so that the spring distortion is assisted by the wedge action of the inwardly moving side bars *d* and *e*.

In order to prevent the screw heads of the screws *n* from scratching the table on which the press is laid, I prefer to provide ribs or the like *m* on the external surfaces of the pressure boards *a* and *b*.

The garment to be pressed is here assumed to be a necktie and this necktie is folded over a holder *f* which may be termed an insertion piece. In the preferred form of holder for use with a necktie, it is composed of two hinged flaps *f¹* and *f²* which are joined by a leather or like flexible strip *f³* suitably let into the flaps. The flaps have also scalloped out parts *f⁴* to act as finger pieces when pulling the necktie out of the press and a recessed part *f⁵* at the top end

of the insertion piece helps to retain the necktie in place on the insertion piece. The purpose of the hinged flaps is to allow the neck band portion of the necktie to be folded between the flaps as the smoothing effect is to be applied mainly to the end portions of the tie. In this way the press may be made of shorter length than has been usual in such push-in tie presses.

10 In use, the tie is folded on the holder with the ends it is desired to press arranged outside when the holder f is folded in book form as shown in dotted lines in Figure 4. The press is then held in the left hand and 15 the sides d and e slightly squeezed to cause the side bars to approach and the pressure boards a and b are thereby caused to move slightly apart. The necktie on the holder is then passed longitudinally in the direction of the arrow in Figure 1 between the pressure boards. To facilitate the insertion of the tie on entering between the boards, the ends of these are bevelled or tapered as indicated at g . An internal slip of cardboard or the like may be inserted inside the tie as at h so as to stretch the material of the necktie t as indicated in Figure 5. To extract the tie from the press, the press is again gripped in the left hand and the insertion piece or holder f gripped by the finger holes f^1 and the tie pulled out still in the direction of the arrow in Figure 1. The degree of smoothing action effected during insertion and withdrawal of the necktie can be regulated by the lateral pressure applied by the left hand to the side bars d and e ; this is an important feature when it is considered that the various materials of which the neckties are made require varying degrees of pressure in smoothing.

15 I claim:

1. A garment press comprising in combination, two substantially parallel pressure boards, spring means fixed to and located laterally of said pressure boards to press them towards one another and retain them coupled in substantially parallel spaced relation and a rigid garment holder over 50 which the garment is folded and adapted to be pushed longitudinally between the pressure boards.

2. A garment press comprising in combination, two substantially parallel pressure boards, spring means fixed to and located laterally of said pressure boards to press them towards one another and to retain

them coupled in substantially parallel spaced relation, a rigid insertion piece over which the garment is folded and adapted to be pushed longitudinally between said pressure boards and means for distorting said springs to pry the pressure boards apart to facilitate the insertion of the garment and insertion piece.

3. A garment press comprising in combination, two substantially parallel pressure boards, curved springs joining said boards at the sides and coupling them resiliently in substantially parallel spaced relation, side bars fixed to said curved springs so that on being pressed together laterally they distort the springs to move the pressure boards apart and a garment holder on which the garment to be pressed is folded and inserted longitudinally between said pressure boards.

4. A garment press comprising in combination, two substantially parallel pressure boards, curved springs joining said boards at the sides and coupling them resiliently in substantially parallel spaced relation, side bars fixed to said curved springs so that on being pressed together laterally they distort the springs to move the pressure boards apart, wedge faces on the adjacent sides of said pressure boards and side bars to cooperate in moving the pressure boards apart and a garment holder on which the garment to be pressed is folded and inserted longitudinally between said pressure boards.

5. A garment press comprising in combination, two substantially parallel pressure boards having smooth faces opposite one another and external ribbed surfaces, a plurality of C-shaped springs joining said boards at each side, the C-shaped springs on opposite sides having their convexities facing one another, side bars on each side fixed to said C-shaped springs and nesting in said convexities and a rigid garment holder adapted to be pushed longitudinally between said pressure boards and side pieces.

6. A garment press comprising in combination, two substantially parallel pressure boards, a plurality of springs joining said boards on opposite sides, side bars fixed to said springs and arranged on being approached to pry the pressure boards apart and a garment holder for inserting between said pressure boards and having two flaps and a flexible hinge joining said flaps, substantially as described.

ROBERT EDWARD TWIGG.
